UNITED STATES PATENT OFFICE.

ELMER ELSWORTH HANNA, OF CHICAGO, ILLINOIS.

FLUID-PRESSURE RIVETING-MACHINE.

No. 823,273.

Specification of Letters Patent.

Patented June 12, 1908.

Application filed May 15, 1903. Serial No. 157,284.

To all whom it may concern:

Be it known that I, ELMER ELSWORTH HANNA, a citizen of the United States, residing at Chicago, in the county of Cook and State of Illinois, have invented certain new and useful Improvements in Fluid-Pressure Riveting-Machines, of which the following is a specification.

The principal object of this invention is to provide a simple, economical, and efficient fluid-pressure riveting-machine with a system of compound levers for transmitting power and motion from the attached engine-cylinder to the riveting-tools quickly at first and finally, or during the riveting operation, in a substantially uniform manner, as will more fully hereinafter appear.

The invention consists principally in a fluid-pressure riveter in which there are combined a portable bifurcated supporting-frame, a plunger slidably mounted in the head of one arm thereof and bearing a desired tool, a main operating-lever pivotally mounted in the supporting-frame, link mechanism pivotally connected with the main operating-lever and the plunger, a fluid-pressure cylinder pivotally connected with the frame of the machine, a reciprocating piston mounted in such cylinder and provided with a projecting piston-rod, link mechanism pivotally secured to the frame of the machine and to the piston-rod, and an intermediate lever pivotally secured to the piston-rod and to the main operating-lever.

The invention consists, further and finally, in the features, combinations, and details of construction hereinafter described and claimed.

In the accompanying drawings, Figure 1 is a side elevation of a machine with the plunger portion in section as it appears when constructed in accordance with these improvements, and Fig. 2 a plan view of the same looking at it from above.

In the art to which this invention relates it is well known that it has long been desired to provide a fluid-pressure riveter with a system of compound levers interposed between the prime mover and the riveting-tool in such a manner as to obtain a substantially rapid movement at first and finally a substantially uniform motion at reduced speed, but greatly increased transmission of pressure during the riveting operations. To provide such a machine, this invention is principally designed.

In constructing a fluid-pressure riveter in

accordance with these improvements I make a bifurcated frame portion *a*, substantially C-shaped when viewed in side elevation, as shown in Fig. 1. Slidably mounted in the head *b* in the upper arm of the C-shaped frame is a plunger *c*, provided with a riveting or other operating tool *d*, screw-threaded therein. The lower arm of the C-shaped frame opposite the operating-tool is provided with an anvil *e*. In place of this riveting-tool and anvil a punch and die may be used, so that the punching of holes in metal sheets may be accomplished just as easily with this machine as the heading of rivets, all of which will be understood and appreciated by those skilled in the art. To operate this plunger, a main operating-lever *f* is provided and fulcrumed at *g* in an upper extension of the machine-frame substantially in line with and above the slidable plunger. Link mechanism *h* is also provided and pivotally connected with the forward projecting end of the main operating-lever and with the plunger mechanism, so that during the movements of said operating-lever motion is transmitted to the slidable plunger, and thereby to the riveting or other operating tool.

To transmit power and motion to the main operating-lever, a fluid-pressure cylinder *i* is provided and pivotally secured in the frame of the machine at *j*, so that it may oscillate thereon to accommodate the movements of the other parts, as will more fully hereinafter appear. A reciprocating piston *k* is movably mounted in this fluid-pressure cylinder and provided with a projecting piston-rod *l*. An intermediate link *m* is provided and pivotally connected with the rearward projecting end of the main operating-lever and with the forward end of the reciprocating piston. To control or govern the actions of the intermediate link, a link or links *n* are provided and pivotally secured to the intermediate link and reciprocating piston-rod at their common pivotal points and also to the frame of the machine at *p*.

By the foregoing arrangement or system of levers it will be seen that the extreme outer end of the piston is during its reciprocations not only compelled to reciprocate, but that the forward end is also compelled to move in the arc of a circle the center of which is at *p* and that thereby the plunger, through the instrumentality of the intermediate link *m*, main operating-lever *f*, and link *h* is given a rapid movement at first or until it reaches

approximately the last five inches of its stroke or during the riveting operation, when it is given substantially uniform movement at reduced speed, but greatly increased pressure, all of which will be understood and appreciated by those skilled in the art.

To sustain the machine in position so that the portable frame portion, with the lower anvil portion, is moved while the plunger remains substantially stationary, the plunger mechanism is provided with a pair of projecting studs *q*, extending to each side of the machine (see Fig. 2) and out through elongated openings *t* in the frame-head. Hanger mechanism in the shape of chains *u* or the like is provided and secured to these projecting studs and to a second set of studs *w* on the fluid-pressure cylinder, so that the parts may be sustained in position and the desired movement obtained. By this arrangement the rivets may be placed in position with the preliminarily-formed head uppermost and the cylindrical part projecting down through the plates, thus enabling the operator to place as many rivets preliminarily in position as he may desire.

I claim—

1. In a riveting-machine, the combination with a supporting-frame having a sliding plunger therein, of means for moving said plunger at a relatively rapid and gradually-decreasing speed and for continuing the final movement at a substantially uniform speed and maximum pressure, said means including a main lever fulcrumed in the frame above the plunger, a link connection between one end of said lever and the plunger, a link pivoted to the frame, a link connection between said link and the opposite end of said lever, and means for moving the link pivoted to the frame about its pivot.

2. In a fluid-pressure riveter, the combina-

tion with a supporting-frame having a sliding plunger therein, of means for moving said plunger at a relatively rapid and gradually-decreasing speed and for continuing the final movement at a substantially uniform speed and maximum pressure, said means including a reciprocating piston, a primary lever fulcrumed intermediate its ends above said plunger, a link connection between one end of said primary lever and the plunger, a link pivotally supported on the frame and having a pivotal connection with the reciprocating piston, and a link connecting said last-mentioned link and the opposite end of the primary lever.

3. In a fluid-pressure riveter, a portable frame provided with an anvil, a movable plunger positioned in the frame above the anvil, a fluid-pressure cylinder supported in the frame, a piston therein, lever-and-link connections between said piston and plunger to effect the movement thereof, and hanger mechanism for suspending said frame connected to said plunger and said fluid-pressure cylinder.

4. In a fluid-pressure riveter, a portable frame provided with an anvil, a plunger movably supported within the frame above the anvil and provided with studs projecting laterally to each side of the frame of the machine, a fluid-pressure cylinder supported in the frame, a piston therein, lever-and-link connections between said piston and the plunger, and suspension-chains having their ends secured respectively to the laterally-projecting studs of the plunger and to the fluid-pressure cylinder.

ELMER ELSWORTH HANNA.
